AXMINSTER LOOM

Edward J. Dacey, Philadelphia, Pa., assignor to
Crompton & Knowles Loom Works, Worcester,
Mass., a corporation of Massachusetts

Application December 20, 1937, Serial No. 180,814

9 Claims. (Cl. 139—10)

This invention relates to improvements in tube frames for Axminster looms and it is the general object of the invention to provide a construction permitting the use of a strong hook and ear for attachment to the transporting chain.

As heretofore constructed it has been customary to provide Axminster tube frames with ears secured to the ends of the frame and offset outwardly for engagement with the double links of the chain. The attaching hook passes through a slot formed in the ear and this slot weakens the ear so that the latter is not suitable for use with long heavy tube frames. It is an important object of my present invention to provide a construction employing a relatively heavy ear which is substantially straight, together with an attaching hook which lies wholly outside the ear so that the latter need not be offset or slotted.

In the usual construction the upper tongue of the ear extends into the double link of the transporting chain while the hook engages the inner of the link members and lies outside the latter. It is a further object of my present invention to project the hook as well as the ear into the space between two link members of the chain. By this construction the wear incident to attaching and detaching the tube frame is distributed to two chain members, one engaging the hook and the other engaging the ear.

It has been customary heretofore to construct the transporting chains of Axminster looms of alternate single and double links, the latter having holding relation with the ears and hooks of the tube frames. It is a further object of my present invention to provide a new form of chain having a triple link to replace the double link of the former construction. My improved chain in effect is the old type of chain with a third link added to each double link, the space between the third link and the adjacent member of the double link being sufficiently wide to receive both the hook and the ear of the tube frame.

When using the improved chain just described I prefer to have the hook latched over the intermediate or center member of the triple link. This places the supporting strain on substantially the same part of the link as formerly. In older constructions, however the ear which extends into the double link has been formed with shoulders so that the tube frame when upside down rests on the longitudinal center of the chain. In order to retain these same conditions as nearly as possible it is a further object of my present invention to provide the hook with a supporting lug to engage the intermediate member of the triple link

when the tube frame is upside down. In order that the spool may be held against accidental turning it is a further object of my invention to provide a friction pad normally engaging the spool head but moved to releasing position by the hook when the latter is pushed from the chain.

With these and other objects in view which will appear as the description proceeds, my invention resides in the combination and arrangement of parts herein described and set forth.

In the accompanying drawing, wherein a convenient embodiment of my invention is set forth,

Fig. 1 is a vertical longitudinal section through one end of the tube frame showing the hook in supporting position and the clutch approaching hook releasing position, the spool and tuft yarn tubes being shown in elevation.

Fig. 2 is an end elevation taken in the direction of arrow 2, Fig. 1.

Fig. 3 is a plan view looking in the direction of arrow 3, Fig. 1.

Fig. 4 is a detailed vertical section on line 4—4, Fig. 1.

Fig. 5 is a plan view of an improved chain, and

Fig. 6 is a vertical transverse section through the tube frame taken on line 6—6 of Fig. 1.

Referring to the drawing, the yarn spool S rotates in a bearing 10 secured to the upper surface of a hollow metal tube 11. The latter carries the tuft tubes T of usual construction, while the clutch C may have an inwardly and downwardly inclined lip 12 and a vertical web 13 carrying a pivot 14 to be received by the forward end of a transfer lever. A rod 16 is pivoted to the upper part of the web 13 for the purpose of rocking the tube frame about the stud 14 when in cloth forming position. The clutch may have the usual side wings 17 and be operated in substantially the usual manner.

A block 20 fits into the end of the tube 11 and has an internal square slide bearing 21 extending therethrough. The block may be held in position in any approved manner as by welding to the tube and has attached to the inner end thereof a bearing plate 22 held in position by screws 23 which pass into the block. The plate 22 has a cylindrical slide bore 24 for a purpose to be described.

The ear or bracket 30 of the tube frame shown is formed of a flat strip of sheet metal, the lower ends of which are held to the block 20 by screws 31 and ear extends upwardly as indicated in Fig. 1 without being offset in the usual way. The lower part of the bracket has a square horizontally extending bore 32 in alignment with the bore 21 of the block. If desired the upper end of the ear 33

may be reduced as at 33 to define shoulders 34, see Fig. 2.

The hook member 40 is of the sliding type and is formed of a flat rigid metallic strip the upper end of which may be bent in the form of a hook 41 in a direction away from the tongue 33. The lower end of the hook member has welded thereto a square gudgeon 42 which extends through the bore 32 and into the bore 21 of block 20. A reduced cylindrical extension 44 extends through the remainder of the bore 21 and the bearing 24 to project inwardly beyond the plate 22 sufficiently to receive a collar 45 held in adjusted position along the extension 44 by means of a set screw 46. A spring 47 around the extension is interposed between the plate 22 and the slide bearing 42 and exerts a compressive force tending to move a hook member 40 outwardly or away from the block 20 and bracket 30, this motion being limited by the collar 45.

The chain H is formed of single links 50 as shown in Fig. 5 between which are located triple links formed of members 51 and 52 which are very similar to corresponding parts of the ordinary tube frame, and an additional third member 53 spaced from member 52, as suggested in Fig. 5. This space is determined by the length of collars 54 on the pins 55 which hold the links of the chain together.

30. The chain sprocket 60 may be substantially of the usual form and has a series of pockets one of which is shown at 61 to receive the tongue 33. The hook member is provided with a lug 65 spaced below the hooked end 41 a distance somewhat greater than the width of the intervening part of link 52 for a purpose to be described.

In order that the spool may be held against accidental rotation but free to turn when pulling off I provide a brake lever 70 pivoted at 71 to the bearing 10 and form this lever with an upper friction arm 72 adapted to bear against the web 73 of the spool head 74. The lever also has a lower arm 75 projecting through a narrow opening 76 in the ear 30 and extending beyond the latter sufficiently to be engaged by the hook 40 when the latter moves to chain releasing position. A spring 77 between the bearing 10 and the arm 75 holds the upper part 72 of the lever against the spool to prevent turning of the latter while the tube frame is being transported by the chain.

50. In operation, the chain will be given successive step by step motions by mechanism not shown but well understood to place the tube frames one at a time in the position indicated in Fig. 2. When 55 the tube frame arrives in this position the bracket 30 will extend through the space 80 between link members 52 and 53, as will also the hooked end 41 disposed over the link member 52. In this position the lug 65 is under the member 52. The 60 relatively heavy compression spring 47 holds the hook in the position shown in Fig. 1, the collar 45 determining its position.

When the tube frame is to be removed from the chain the clutch moves inwardly or to the left from the position shown in Fig. 1, the lip 12 raising the tube frame slightly to lift the hook 41 above the link member 52, after which continued inward motion of the clutch will effect engagement of the wall 13 with the hook member 40 and the latter will move to the left against the action of spring 47. The square bearing 42 and bore 21 of the block require the hook to move with a right line motion until the hook 41 is entirely clear of the member 52. As the clutch 75 nears the end of its inward motion it will force

the hook member 40 against the end 75 on the lever 70 and rock the same slightly in a counter-clockwise direction as viewed in Fig. 1 against the action of spring 77 to remove the frictional braking force from the spool.

5 The clutch thereupon descends in well-known manner and the tube frame is rocked about the stud 14 during the tuft forming operation, after which the clutch is raised to cause the tongue 33 and the hook 40 to enter the space 80 of the corresponding triple link. The clutch then moves outwardly or to the right as viewed in Fig. 1 and hook 41 passes over a link member 52. During this motion of the hook the lever 70 returns to its normal braking position with respect to the spool 15 under the action of spring 77. As the clutch nears the outer end of its motion the collar 45 will engage the plate 22 and the hook will be properly located with respect to the link member 52.

10 As the tube frame travels with the chain the 20 time will come when it will be over a guide sprocket not shown, but forming the usual part of an Axminster loom, at which time the tube frame will be upside down. The weight of supporting the hook will thereupon be transferred from the 25 hook 41 to the lug 65. The latter engages a link member 52 at a point not far removed from the longitudinal center of the part of the chain defined by links 50, 51 and 52. The strain of supporting the tube frame in this inverted position 30 is therefore borne by member 52 and preferably though not necessarily is not carried by the member 53 or the collars 54. If desired, however, the latter may have engaging relation with respect to the shoulders 34, but I prefer to depend upon 35 the lug 65 to support the tube frame when inverted.

It is to be understood that the matter described and shown in connection with Fig. 1 is duplicated at the opposite end of the tube frame, and that 40 the clutches and operating mechanism therefor, together with the sprocket 60, are substantially the same as those found in the usual Axminster loom.

The brake mechanism involving the arm 70 45 and the relation which it sustains to the hook member 40 is not specifically claimed herein but is set forth and claimed in a divisional application.

From the foregoing it will be seen that I have 50 provided a tube frame wherein the hook lies entirely outside the ear or bracket 30 and that the latter can be made without bending and without the extensive perforation and slotting as heretofore. It will also be seen that the chain has 55 been modified by adding a third member to the usual double link and that both the bracket and the hook pass into the space between the third member and the adjacent member of the usual double link, thereby causing engagement of two 60 members of the chain and distributing the wear as distinguished from former practice where both the hook and the bracket engage the same chain member. It will also be seen that the lug 65 supports the tube frame when inverted and 65 places the load of the frame on the chain at a point close to the longitudinal center of that part of the chain corresponding to earlier types of chains. Also, motion of the hook member 40 releases lever 70 to relieve the friction brake on the 70

Having thus described my invention it will be seen that changes and modifications may be made therein by those skilled in the art without departing from the spirit and scope of the invention.

tion and I do not wish to be limited to the details herein disclosed, but what I claim is:

5 1. In an Axminster loom, a transporting chain having three transversely spaced links, a tube frame, an ear secured to the tube frame and extending into a space between an outer link and the center link, a supporting hook mounted on and movable relatively to the ear and extending into said space, and an engaging sprocket for 10 the center link and the other outside link.

15 2. In an Axminster loom, a transporting chain having three transversely spaced links, a tube frame, an ear secured to the tube frame and extending into the space between one of the outer links and the center links, a hook for supporting the tube frame mounted on the latter and movable relatively to the ear and extending into said space and having holding relation with respect to the center link, and a sprocket to have driving 20 relation with the center link and the other outer link.

25 3. In an Axminster loom, a transporting chain having a triple link including a center and two outer links spaced from each other transversely of the chain, a tube frame, an ear secured to the tube frame extending into the space between the center link and one of the outer links, a supporting hook for the tube frame mounted on the latter and movable relatively to the ear and normally spaced from the latter, said hook extending into said space and having engagement with one of the links defining the lateral limits of said space, means to move the hook toward the ear and away from said one of the links, and a sprocket to engage the center link and the other of said outer links.

40 4. In an Axminster loom, a transporting chain having a triple link comprising a center and two outer links spaced from each other transversely of the length of the chain, a tube frame, an ear secured to the tube frame and extending into the space between one of the outer links and the center link, a hook supported by the tube frame and movable relatively to the ear and extending into said space for engagement with the center link, means to move the hook in said space away from the center link toward the ear to disconnect the tube frame from the chain, and a driving 45 sprocket to engage the center link and the other of said outer links.

45 5. In an Axminster loom, a transporting chain having a pair of spaced links, a tube frame, an ear secured to the tube frame and extending into the space between said links and lying adjacent one of said links, a hook for supporting the tube frame on the chain, means to mount the hook for movement on the tube frame relative to the ear,

said hook extending into the space between the links and engaging the other of said links, whereby wear incident to engagement of the ear and hook by the chain will be distributed to the two links, and means to move the hook toward the ear and away from the link normally engaged therewith.

5 10 6. In an Axminster loom, a tube frame, a transporting chain having a pair of laterally spaced links, an ear secured to the tube frame and extending into the space between the links adjacent one of the latter, a hook mounted on the tube frame for movement toward the ear and extending into the space between said links, said hook having a part bent in a direction away from the ear for engagement with the other of said links, and means to move the hook toward the ear and away from the link normally engaged therewith.

15 7. In an Axminster loom, a transporting chain, a tube frame, an ear secured to the tube frame and extending into engaging relation with respect to the chain, a supporting hook for the tube frame located wholly on that side of the ear remote from the longitudinal center of the tube frame and having holding relation with respect to the chain, and a sliding support for the hook extending through the ear and into the tube frame to establish supporting relation between the hook and the tube frame.

20 8. In an Axminster loom, a transporting chain, a tube frame, an ear secured to the tube frame and extending into engaging relation with respect to the chain, a hook for the tube frame to engage the chain, said hook lying entirely on that side of the ear remote from the longitudinal center of the tube frame, a slide bearing on the tube frame, a slide member secured to the hook and extending through the ear and into the slide bearing to establish supporting relation between the tube frame and the chain, and means to move the hook relatively to the ear out of supporting relation with respect to the chain.

25 9. In an Axminster loom, a transporting chain, a tube frame, an ear secured to the tube frame and extending into engaging relation with respect to the chain, a supporting hook for the tube frame located wholly on that side of the ear remote from the longitudinal center of the tube frame and having holding relation with respect to the chain, a sliding support for the hook extending through the ear and into the tube frame to establish supporting relation between the hook and the tube frame, and means to limit motion of the supporting hook in a direction away from the ear.

30 35 40 45 50 55 EDWARD J. DACEY. 55
